UNITED STATES PATENT OFFICE.

THOMAS CLIFF, OF DETROIT, AND ALMER E. ARBUCKLE, OF HIGHLAND PARK,
MICHIGAN; SAID CLIFF ASSIGNOR TO SAID ARBUCKLE.

STEAM-GENERATOR.

1,279,514.

Specification of Letters Patent. Patented Sept. 24, 1918.

Application filed February 15, 1917. Serial No. 148,841.

To all whom it may concern:

Be it known that we, THOMAS CLIFF, a citizen of the United States, residing at Detroit, in the county of Wayne and State of Michigan; and ALMER E. ARBUCKLE, a citizen of the Dominion of Canada, residing at Highland Park, in the county of Wayne and State of Michigan, have invented a new and useful Steam-Generator, of which the following is a specification.

This invention relates to steam generators of the instantaneous or flash generating type, and it consists in the novel features of construction and operation as hereinafter set forth and claimed.

The principal object of the invention is to provide simple and efficient means for rapidly generating and storing steam for use as a motive medium, in which the construction and operation is such as to enable the introduction of the heat and expansive energy of exploded charges of compressed gases directly into a confined body of water at the instant of ignition so as to utilize the force of the impact resulting from the explosion to diffuse and atomize the water simultaneously with the discharge of the hot gases of combustion therethrough, and thus subjecting the liquid atoms to intense heat and pressure in a manner to cause them to rapidly vaporize and flash into steam.

The invention further provides for means controlled by the generator to supply water thereto and to automatically maintain the water supply at a predetermined volume and level.

In the accompanying drawings is illustrated a vertical sectional view of the preferred structural arrangement of the essential features of our invention, in which 1 represents a compression and combustion cylinder, having an inlet port 2 for the admission of an explosive mixture which may be supplied by a liquid fuel carburetor 3, or from other suitable source. The cylinder is provided with a piston 4 operably coupled by a connecting rod 5 with a crank shaft 6 which is adapted to be driven by any suitable means for actuating said piston to draw in and compress a gaseous charge to be exploded therein by a suitable spark plug or igniter 7 communicating with the working space of said cylinder. The outer end of the combustion cylinder, which is open, is provided with a surrounding flange 8 upon which

is securely mounted by bolts 9 the open end of a steam and water chamber 10, which communicates with and incloses the open end of said cylinder. Mounted in a tapered seat 11, formed in the end of the cylinder opening 60 into the chamber 10, is a tapered disk valve 12 having a conical upper face from which a stem 13 extends axially through an open guide 14 abridging said chamber, and embracing said stem and interposed between 65 the valve and said guide is an expansive coiled spring 15 which normally retains said valve seated to close communication between said cylinder and said chamber.

Extending through the wall of the chamber 10, at a point slightly above the valve 12, is a water inlet passage 16, which communicates through a pipe 17 with a water supply tank 18 and communicating with the dome or steam space of the chamber 10 and with 70 the upper end of the tank 18 is a pipe 19 for the admission of steam to equalize the pressure upon the water in said tank with the pressure in said chamber. Water is forced under pressure into the supply tank by 75 means of a pump 20 having the piston 21 therein driven by an eccentric connection 22 with the shaft 6, and water is delivered to the pump through a pipe 23 leading to a source of supply and having a check valve 80 24 therein between which and said pump a branch pipe 25 connects with an inlet opening 26 in the lower end of said tank. This opening is normally closed by a float controlled valve 27, the float 28 for which is provided at its upper end with a stem 29 supported to move axially through a guide 30 abridging said tank, and the lower end of the float is provided with a sleeve 31 movably extended through a support 32 abridging 85 the lower end of the tank, by means of which said float is guided to operate vertically with the variations in the water level and in axial alignment with the inlet opening 26 of said tank. The valve 27 controlling said opening is provided with a stem 33 fitting freely within the sleeve 31 at its upper end, and in which it is movably held against axial displacement by means of a pin 34 inserted transversely therethrough and 90 through a diametric slot 35 in said stem. An expansive coiled spring 36 embracing said stem is interposed between the valve 26 and the end of said sleeve for exerting an outward yielding tension thereon to permit 100 105 110

of limited relative movement of said valve and float.

With the parts thus constructed and associated, the operation of the device will be as follows: The pump being constantly driven together with the piston of the combustion cylinder through the application of driving power to the crank shaft thereof, water will be drawn in through the check 5 valve 24 and forced out by the pump through the lines 23 and 25 into the tank 18 through the opening 26. The valve 27 therein will be caused to recede from its seat against the tension of the spring 36 10 and weight of the float under the pressure of the inflowing water, and upon the succeeding suction stroke of the pump said valve will re-seat to check the outflow of water from the tank until the water level 15 20 therein has reached a sufficient height to raise the float and cause the pin 34 to engage the end of the slot of the valve stem and lift the valve from its seat, when the action of the pump will be neutralized by 25 a return flow of the water from the tank thereto.

The water is thus maintained in the tank at a suitable level to insure the delivery through the pipe 17 and inlet 16 to the steam 30 generating chamber 10 of a sufficient volume to immerse or cover the valve 12 of the combustion cylinder. The explosive charges of gaseous mixture are drawn into the cylinder 1 through the inlet port 2 from 35 the carburetor 3 on the suction stroke of the piston 4, and upon the completion of the return stroke of said piston the charge is compressed and simultaneously fired by the igniter 7. The force of the explosion exerted upon the valve will open and impel it with violent impact against and through 40 the body of water in the chamber 10, causing the agitation and diffusion of the water and subjecting it in an atomized condition 45 directly to the intense heat and pressure of the inrushing burning gases exhausting

from the combustion cylinder, whereby the water will be instantly flashed into steam at a high temperature with each explosive stroke of the piston. The steam thus generated will be retained and accumulated within the chamber 10 by the closing of the valve partly under the tension of the spring 15 and principally by the steam pressure developed in said chamber, and this pressure may be relieved and controlled by any suitable known means for such purpose. A discharge pipe as shown at 37 communicating with the dome of the steam chamber may be provided for the delivery of the 60 steam for use in any desired manner.

It will be seen from the above described manner of introducing the burnt gases into the water, that the water will be subjected to the disintegrating force of the explosion 35 and also to direct contact with the intense heat and pressure resulting therefrom at the point of highest temperature to most effectively cause the instantaneous generation of steam.

We claim:

In a steam generator, the combination of a power driven engine having a compression and combustion cylinder for exploding gaseous charges, a casing inclosing one end of 75 said cylinder and forming a chamber communicating with the combustion space thereof, a spring pressed valve in said chamber normally closing communication with the combustion space of said cylinder and subject to open by the force of an explosion 80 therein, pumping means controlled by the engine for introducing water into said chamber upon said valve, and means controlled by the pumping means to automatically regulate the delivery of water to said chamber.

In testimony whereof, we sign this specification.

THOMAS CLIFF.
ALMER E. ARBUCKLE.
